L. VALLAS

VENTILATOR

Filed June 21, 1923

UNITED STATES PATENT OFFICE.

LIONEL VALLAS, OF CHICAGO, ILLINOIS.

VENTILATOR.

Application filed June 21, 1923. Serial No. 646,738.

To all whom it may concern:

Be it known that I, LIONEL VALLAS, a citizen of the United States, and a resident of Chicago, in the county of Cook and State 5 of Illinois, have invented certain new and useful Improvements in Ventilators, of which the following is a description, reference being had to the accompanying drawing, which forms a part of my specification.

10 My invention relates to a ventilator of the type more especially intended for use on the roofs of buildings, whereby the vitiated or foul air of the building interior will be automatically exhausted therefrom 15 through the action of the outer air currents.

The invention has for its object the provision of a ventilator of the character referred to, which will provide a true siphon or exhausting action by means of the passing or moving outer air currents without the use of other means; a ventilator having no movable parts and wherein down drafts or currents will be prevented, while at the same time a storm-proof ventilator provided 20 and rain and snow prevented from entering 25 the exhausting or eduction portion thereof.

The objects and advantages of my invention will be more readily comprehended from the detailed description of the accompanying drawing, wherein:—

Figure 1 is a perspective view of my improved ventilator looking downwardly.

Figure 2 is a vertical sectional view thereof.

Figure 3 is a bottom plan view.

In the particular exemplification of the invention as disclosed in the drawing, it comprises the main conduit or exhausting portion indicated at 10, preferably cylindrical and of any desired height and cross sectional dimensions. The conduit is adapted to be suitably secured about the flue or opening through the roof of a building communicating with the interior of the building in order that the conduit may act as an eduction member for the outward passage of the vitiated or foul air from the building interior. The eduction conduit is preferably of similar dimensions throughout.

50 The exterior side of the eduction conduit 10 is provided with a plurality of air directing members 11, arranged at equi-distances apart and preferably at diametrically opposite points as more clearly shown in Figure 3. These air directing members 11 each con-

sist preferably of a single sheet of suitable metal bent into the arcuate form shown in Figure 3 and preferably sheared so as to have the sides of the members slope downwardly toward the conduit 10 below the intermediate portions at the bottoms of the members 11, as shown at 12 in Figure 2. The sides of the members 11 are secured to the eduction conduit 10 in any suitable manner, as by rivets or otherwise, as shown at 13. The upper ends of the members 11 are preferably arranged in the same horizontal plane as the top of the eduction conduit 10 and these members 11 are of the same dimensions throughout from top to bottom so as to provide the same area at the tops or discharging ends of the siphon members 11 as at the bottom or intake ends thereof. With this construction, no obstruction or restriction is provided to offer resistance to light or delicate exterior air currents in their upward passage through the siphon inducing members 11.

The siphon inducing members 11 are in turn surrounded by an annular member or band 14 which is preferably of the same width as the width of the intermediate portions of the siphon inducing members 11. The circumferential band 14 is secured in any suitable manner to the siphon inducing members 11, as for example by rivets, and not only reinforces the siphon members 11, but at the same time provides auxiliary siphon passages intermediate of members 11, as shown at the points 15. The top of the band or member 14 is preferably arranged flush with the tops of the siphon members 11 and the top of the eduction conduit 10.

55 The fastening means or rivets, whereby the member or band 14 is secured to the siphon members 11, are also preferably employed to support suitable brackets 16 which are bent outwardly into the somewhat horizontally disposed loop or U-shape formation more clearly shown in Figure 2 so as to extend outwardly across the tops of the siphon members 11 and the band 14 to a predetermined extent as shown in Figure 2. The intermediate vertically disposed portions of the brackets 16 provide support for a second circumferential band 17 which is preferably arranged so as to have the lower perimeter or edge of the band extend into a horizontal plane slightly beneath the

plane of the top of the band 14; while the upper perimeter or edge of the band 17 is intended to preferably extend slightly beyond the tops of the vertically disposed portions of the brackets 16.

These brackets 16 have their upper portions disposed inwardly, with the immediate ends arranged in an upward inclining manner as shown at 18 in Figure 2, to receive a top or hood member 19, which is preferably dished or cone-shaped as shown in Figures 1 and 2, to provide a proper moisture or water-shed. The diameter at the base of the top or hood portion 19 is less than the diameter of top band 17 and preferably substantially equal to the diameter of the band member 14, so that the hood or top 19 will be disposed across the tops of the siphon members 11 as well as the siphon passages 15 formed intermediate of the respective siphon members 11 and the band 14.

With the top band 17 arranged to extend slightly above the vertically disposed portion of the brackets 16, it is apparent that the upper perimeter of the band 17 is arranged in a horizontal plane somewhat above the plane of the perimeter of the top or hood 19; while at the same time a circumferential space between band 17 and the perimeter of hood 19 is provided, as more clearly shown in Figures 1 and 2.

The ventilator is preferably made of weather-resisting material, such as copper or galvanized metal, with the edges of the respective portions or members preferably beaded or crimped so as to reinforce the same; and the eduction member 10 is also preferably provided with a damper as at 20 pivoted in any suitable manner at 21, and preferably provided with a weight as at 22 which automatically causes the damper to swing into open position.

With my improved construction wherein the siphon tubes or members 11 are encircled by the circumferential member or band 14, a plurality of siphon chambers disposed entirely about the exhausting or eduction conduit 10 are provided and free and ample suction through the siphon tubes or passages is provided as the siphon passages are of equal dimensions throughout from top to bottom thus offering no restriction to the air currents; the siphon passages inducing an exhausting action at the top between the cap and the outer band or member 17; the latter preventing any down draughts through the ventilator as well as providing

a weather-proof construction against the entry of snow and rain.

The construction shown and described I believe is the simplest and best embodiment of my invention which has been described in terms employed merely as terms of description and not as terms of limitation, as structural modifications are possible and may be made without, however, departing from the spirit of my invention.

What I claim is:—

1. A ventilator of the character described, comprising a vertically disposed eduction member of equal transverse dimensions throughout, a plurality of siphon inducing channels arranged circumferentially about the eduction member, each of said channels being of equal transverse dimensions throughout and terminating flush with the upper end of the eduction member, bracket members secured to the side walls of the channels, bent laterally outward across the upper ends of the channel side walls, thence upwardly and then inwardly, a hood member secured to the upper inner ends of the bracket members in spaced relation with the upper ends of the eduction member and said channels, a band secured to the upwardly bent portion of the brackets and arranged to extend beyond the tops of the siphon inducing channels and the lower perimeter of the hood member and in spaced relation therewith.

2. A ventilator of the character described, comprising a central conduit, a plurality of arcuate siphon inducing members, disposed about the conduit and of equal transverse dimension throughout and terminating with the top of the conduit, a band disposed about the members, with its upper edge in the same plane as the upper ends of said members and the conduit, whereby auxiliary siphon channels are provided, bracket members secured to the arcuate members and disposed outwardly and upwardly, a conical hood member secured to the upper ends of the bracket members in spaced relation with the tops of the conduit and siphon members and of transverse dimensions equal to the transverse dimensions of the conduit and surrounding siphon chambers, and an encircling band secured to the outwardly disposed portions of the bracket members in spaced relation with the hood and the siphon members and of width greater than the space intermediate of the upper ends of the siphon members, conduit and the hood member.

LIONEL VALLAS.
